UNITED STATES PATENT OFFICE.

GUSTAV W. HEDSTROM, OF CHICAGO, ILLINOIS, ASSIGNOR, BY DIRECT AND MESNE ASSIGNMENTS, TO AMERICAN CAN COMPANY, A CORPORATION OF NEW JERSEY.

DRYING MACHINE.

Application filed December 8, 1922. Serial No. 605,613.

To all whom in may concern:

Be it known that I, GUSTAV W. HEDSTROM, a citizen of the United States, and a resident of Chicago, in the county of Cook and State of Illinois, have invented certain new and useful Improvements in Drying Machines; and I do hereby declare that the following is a full, clear, and exact description thereof, reference being had to the accompanying drawings, and to the characters of reference marked thereon, which form a part of this specification.

This invention relates to improvements in drying machines for drying articles or films on the articles as the latter pass slowly through a drying chamber of the machine, and is herein shown as adapted to the type of drying machine shown in my United States Letters Patent No. 1,472,417, granted October 30, 1923, wherein can ends, within the grooves of which a sealing compound has been applied, are slowly advanced through a drying chamber by combined lifting threads and driving means.

The present improvements relate to means for automatically removing can ends from the upper end or ends of the stack or stacks of can ends by means which facilitate the removal of the can ends from the machine, and the main or principal object of the invention is to provide a take-off device that is so related to the upper end or ends of the stack or stacks that the can ends may be removed one at a time into a discharge chute, from which latter the said ends may be readily removed. As herein shown a single discharge chute is employed and mounted on a fixed part of the machine, and in such a position that one operator, who cares for the feeding of the can ends to the machine, may also remove the can ends from said chute.

Another object of the invention is to provide means at the lower end of the drying chamber, and at the point where the can ends are fed thereinto, to effect safe delivery of the can ends to the lifting threads without liability of the can ends being crushed.

Other objects of the invention are to further improve and simplify drying machines for the purpose set forth, and the invention consists in the elements and combination of elements shown in the drawings

and described in the specification, and is 55 pointed out in the appended claims.

In the drawings:

Figure 1 is a side elevation of a drying machine embodying my invention.

Figure 2 is a plan view thereof. 60

Figure 3 is an enlarged view, partially in section and partially in elevation, and broken between its ends, of the upper part of the drying machine.

Figure 4 is an enlarged fragmentary plan view of a portion of the drying machine and the discharge chute, showing in elevation the means for separately removing or skimming the can ends from the upper ends of the stacks in the drying chamber and 70 65

positing them in the discharge chute.

Figure 5 is a section on the line 5—5 of Figure 4.

Figure 6 is a detail of a latch for holding closed a safety door at the can end feed 75 70 slot of the drying chamber.

As shown in said drawings, 10 designates a supporting standard which is provided at its upper end with wings 11 on which are formed bearings 12 to receive a driving shaft 13, whose function will presently appear. In the present instance the standard 10 is hollow, and it is provided near its upper end with a transverse opening through which the shaft 13 extends. 14 designates an upright 80 shell fixed to and supported on said standard, as by means of screw bolts 15 which extend upwardly through the head 16 of the standard and into threaded openings of a bed plate 17; said bed plate being fixed to 90 the lower margin of the shell 14 by screw bolts 18 extending through the plate and into threaded openings in the thickened lower margin 19 of the shell. Said shell is formed on its inner cylindric wall with a continuous spiral groove extending from end to end 95 thereof to constitute the turns 20, 21 of a spiral thread; the lower or receiving turn of the thread being spaced more widely than the next succeeding or higher threads to facilitate the placement of the can ends in the shell and engage them with the thread. 22 designates an inner fixed member of exterior cylindric formation and disposed axially within the drying chamber 23 formed between said shell and inner member. The said inner member is cut on its outer surface with a spiral groove to constitute a thread,

the turns 24, 25 of which oppose the turns 20 and 21 of the shell thread. Said inner and outer threads terminate short of the top of the shell 14. Said shell is surmounted by 5 a funnel-like top 26 terminating in a chimney 27 to assist in creating a draft of air upwardly through the chamber, admitted through the openings 28 of the plate 17 and intermittently registering openings 29 10 formed in a gear wheel 29' which rests and turns on the plate 17, as in the construction shown in my aforesaid application.

The can ends are delivered to a feed opening 30 at the bottom of the shell into contact with the opposed inner and outer lifting threads; the can ends being directed to said opening by a suitable horizontal guide chute 31 which, in practice, receives the can ends from a machine that applies the sealing compound to the marginal grooves of the ends. 15 The feeding of the cans may be effected manually or automatically and, as herein shown, a feed pawl 32, operated in any suitable manner, is shown as a part of an automatic mechanism for feeding the can ends through 20 the chute 31. The can ends are guided into the influence of said threads by an upper extension 32' of the guide chute and an angle bracket 22' fixed to the inner threaded member 22.

Rising from the gear wheel 29', which is rotated from the shaft 13 through the beveled gears 33, the shaft 34, and a pinion 35, are a plurality of upstanding drive rods 36 35 which are revolved through the drying chamber and serve by contact with the edges of the can ends to force them along the inner and outer threads of the shell and central member 22, and thereby slowly move the 40 can ends through the drying chamber in the manner described in my aforesaid application.

In addition to said drive rods, there are 45 provided at the lower end of the drying chamber short upstanding studs 37 which are fixed to the gear wheel 29' and are located with their upper ends near the plane of the top of the feed slot 30. Said studs are angularly spaced from the drive rods 36, and 50 their function is, first, to steady the can ends when fed into the lifting threads of the chamber, by reason of the two points of contact afforded by the drive rods and said studs, and, second, to eject can ends which 55 may be improperly received at the lower end of the drying chamber for any reason, as, for instance, after the machine has been stopped and it is again started with a can end only partially received by the lower, wider, lifting threads 20. For this purpose 60 the said studs 37 co-operate with a release door 38 at the end of and in line with the receiving slot 30, the door forming one end of the slot. Said door is hinged at 39 to the 65 wall of the shell 14. The door is provided

with a hand piece 40 by which it may be manually opened. The said door is normally locked in its closed position by a light acting spring latch which is readily overcome by slight pressure of an improperly placed can 70 end driven thereagainst by one of the ejector studs 37. The form of latch shown comprises a spherical detent 42 which is partially received in a downwardly opening concave recess 43 in the bottom of the door, 75 and is upheld in said recess by a light spring 44 that is anchored to and is enclosed within an opening in a fixed part of the structure, as best shown in Figures 1 and 6. The said door is adapted to be quickly opened when the latch is overcome by a light spring 41 which is attached at one end to the outer side of the shell, crosses the hinge of the release or ejector door, and is attached to said door beyond said hinge. The curved position of 80 the spring, by reason of its attachment to the curved wall and door, when the door is closed, normally renders the spring ineffective when the door is closed, but renders it active to quickly open the door when the 85 door is forced slightly open.

The said drive rods 36 terminate short of the top of the shell 14 and at about the level of the uppermost turns of the lifting threads of said shell and the central member 22, as best shown in Figure 3. Located at one side of the shell and above the drying chamber is a heavy ring 45. Said ring extends beyond the shell 14, and terminates radially short of the inner threaded member 22. It is fixed to the structure by screw bolts 46, 47, the former extending through the ring into the upper edge of the shell 14, and the latter extending radially through one arm of a bracket 48, the latter of which 90 is fixed as by a bolt 49 to the inner threaded member 22, as best shown in Figures 4 and 5.

50 designates a plate which constitutes the major portion of the bottom of the ring 45 which latter is open at its upper end. Said plate extends inwardly beyond the center of the ring and is formed at its inner margin with a downwardly and inwardly beveled curved edge 51. The said plate is located at about the level of the uppermost 100 lifting threads and in position to engage under the margins of the topmost can ends of the stacks as the latter pass beneath the plate of the takeoff device. The relation of said curved edge 51 and its general angle 105 to the axis of the ring 45 is such that the beveled lifting edge 51 passes smoothly under the topmost can end of a stack as the latter passes beneath the plate, so that said can ends are successively lifted or skimmed 110 off the upper ends of said stacks. In this way a single takeoff device can be arranged at one stationary point in the travel of the stacks of can ends to remove the ends from 115 all the stacks. The relation of the plate 50 120

and its skimming edge 51, which latter lies inwardly beyond the axis of the ring 50, is such that the can ends are successively forced on to said plate 51. By reason of the fact that the skimming edge 51 is lower than the upper face of the plate 50, it will be obvious that when a can end is lifted on to the upper face of said plate 50, it will be thereby supported by reason of the width of the said plate 50, and that the next succeeding can end to be lifted by the edge 51 will cause the latter can end to be forced between the previously lifted can end and said plate thereby serving to move the latter can end into axial relation to the ring, with the last lifted can end beneath the same in position to be likewise forced inwardly by the next succeeding lifted can end. In this manner the can ends will be successively segregated from the stacks, and said ends, as they accumulate in the ring, are gradually raised by the coaction of the last turns of the threads and the beveled lifting edge of the plate through the ring 45.

25 In order to afford a discharge chute of ample length to receive a stack of can ends, the uppermost ones of which are manually lifted therefrom, three or more upstanding guide rods 52 are fixed to said ring to constitute the boundaries of the discharge chute.

30 It will be obvious that I have provided an exceedingly simple, effective and compact means to successively segregate the can ends from the top of the stack and to lift them away from the driving chamber, to be thereafter manually removed from the discharge chute thus formed. While the details of the particular illustrated embodiment have been described with considerable particularity, it will be understood that said details may be varied within the spirit and scope of the appended claims; therefore, it is not the intent to limit the invention to the illustrated details except as to claims wherein they are specifically set forth and as imposed by the prior art.

45 I claim:

50 1. A drying machine for the purpose set forth having an annular drying chamber, and having means to advance therethrough can ends in revolving vertical stacks with the ends in each stack spaced from each other, and a fixed discharge chute provided at its bottom with means to skim the can ends from the tops of said stacks as the latter revolve thereunder.

55 2. A drying machine for the purpose set forth having an annular drying chamber, and having means to advance therethrough can ends in revolving vertical stacks with the ends in each stack spaced from each other, and a fixed discharge chute provided at its bottom with means to skim the can ends from the tops of said stacks, said skimming means

co-operating with the can head advancing means to discharge the can heads through said chute by pressure of can ends which follow.

3. A drying machine for the purpose set forth comprising a vertical annular drying chamber having lifting threads on its walls to engage with the can end rims, means acting on can ends fed into said chamber and co-operating with said threads to cause the can ends to travel through said chamber in angularly spaced revolving stacks and with the ends in each stack spaced from each other, and a fixed vertical discharge chute provided at its lower end with a can end skimming plate provided with a beveled lifting edge in position to engage under the topmost can ends of the stacks as they successively pass beneath the plate.

4. A drying machine comprising inner and outer spiral lift threads forming between them an annular drying chamber, driving means to engage said can ends while resting on said threads to cause the can ends to travel through said drying chamber, a fixed discharge chute and a skimming plate at the bottom thereof having an inner curved beveled edge to engage under the topmost can ends and to transfer them to said chute.

5. A drying machine for the purpose set forth comprising an annular drying chamber with means for admitting can ends thereto to be arranged in parallel groups with the groups angularly spaced about the chamber, combined lifting threads and can end driving means to engage the ends, said means for admitting the can ends embracing a slot opposite the lower lifting threads, and means for rejecting a can end that is improperly directed into said chamber to said lifting threads to avoid crushing the improperly directed can ends.

6. A drying machine for the purpose set forth comprising an annular drying chamber with means for admitting can ends thereto to be arranged in parallel groups with the groups angularly spaced about the chamber, combined lifting threads and can end driving means to engage the ends, said means for admitting the can ends embracing a slot opposite the lower lifting threads, and a door hinged to a wall of the drying chamber at one end of said slot having a light spring held latch.

7. A drying machine for the purpose set forth comprising an annular drying chamber with means for admitting can ends thereto to be arranged in parallel groups with the groups angularly spaced about the chamber, combined lifting threads and can end driving means to engage the ends, said means for admitting the can ends embracing a slot opposite the lower lifting threads, and a door hinged to a wall of the drying chamber at one end of said slot having a light spring

held latch, and a spring connected to said wall and said door and acting to quickly open said door when said latch is overcome.

8. A drying machine for the purpose set forth comprising an annular drying chamber bounded by inner and outer cylindric walls, co-operating lifting threads on said walls adapted to be engaged by the margins of can ends, revoluble driving rods extending through said chamber to engage the margins of the can ends to exert eccentric driving force thereon to rotate said ends, a wall of the drying chamber being provided at the
- lower turns of said threads with a slot to admit can ends to said chambers, short studs 15 angularly spaced from said rods to engage the lowermost can ends as they are fed through said slot, and a swinging normally latched door at the end of said slot adapted to be forced open by force of an improperly 20 delivered can end driven thereagainst by a short stud.

In witness whereof I claim the foregoing as my invention, I hereunto append my signature this 28th day of November, 1922.

GUSTAV W. HEDSTROM.
